UNITED STATES PATENT OFFICE.

EDWIN H. STREETER, OF CLOQUET, MINNESOTA, ASSIGNOR TO WOOD CONVERSION COMPANY, A CORPORATION OF DELAWARE.

STOCK-SPREADING FLOW BOX.

Application filed January 8, 1927. Serial No. 158,834.

In the manufacture of certain types of wall board the stock to be used is mixed with water to form a slurry containing about 95% water and this slurry is flowed on to a screen or Fourdrinier wire in a layer of substantially uniform thickness and passed through a press to remove a large portion of the water and compress the layer into a compact sheet or board. The damp sheets are then passed through a drier to produce a final product of the desired moisture content. The screen or wire on which the stock flows has an intermittent movement to permit the necessary pause for the pressing operation.

It is essential that a substantially level layer of stock be formed on the screen in order to obtain a uniform product when this layer of stock is pressed. Due to the intermittent movement of the screen, it is necessary to control the feed of stock to obtain this uniform layer.

The object of the present invention is to provide a flow box that will automatically form a uniform layer of stock on the screen at all times. I provide a flow box that moves intermittently, the flow box being moved while the screen is stationary. It is mounted on a track extending transversely of the screen and is moved intermittently while the screen is at rest to deposit a layer of stock on the portion of the screen that has just moved into position beneath the path of travel of the flow box. The flow box then remains at rest at one side of the screen while the section of the screen on which the layer of stock has been placed, moves forwardly toward the press and when the screen stops, the flow box moves automatically to the other side to deposit another layer of stock.

Suitable means are provided for automatically starting and stopping the flow box and coordinating its movements with those of the screen. Various devices may be employed for this purpose and controlled by a portion of the screen or other apparatus associated therewith so that the feed mechanism of the flow box will be actuated when the screen is at rest.

By employing a moving flow box, I obtain a layer of stock of uniform thickness throughout the entire width of the screen. At the same time, the stock is permitted to drain uniformly before the screen is again put in motion and the pulp formation is not dis-

turbed by the starting and stopping of the screen.

In the accompanying drawings I have shown one form of the invention. Fig. 1 is a transverse, vertical, sectional view of the Fourdrinier wire or screen showing the flow box in section.

Fig. 2 is a similar view at right angles to Fig. 1, viewed from the right in Fig. 1.

Fig. 3 is a similar view, viewed from the left of Fig. 1.

Fig. 4 is an enlarged, sectional view on line 4-4 of Fig. 1.

Fig. 5 is an enlarged, sectional view in the same plane as Fig. 1.

Fig. 6 is a detailed view of the track on which the flow box travels on line 6-6 of Fig. 1.

Fig. 7 is a similar view on line 7-7 of Fig. 1, and

Fig. 8 is a diagrammatic view of the electric circuits by means of which the movement of the flow box is controlled.

Referring to the drawings the reference numeral 1 designates the wire or screen of a Fourdrinier machine of the usual construction on which the stock is laid in a substantially even layer and delivered to a press (not shown) where it is compacted to the desired degree. From the press the stock is delivered to a drier. The machine may be employed in the manufacture of wall board of the type described and claimed in the co-pending application of Howard F. Weiss, Serial #470,967, now Patent No. 1,631,171 granted June 7, 1927, or it may be employed in the manufacture of other fibrous products in which the fiber stock is formed in a slurry and laid on the screen prior to pressing and drying. The wire or screen is in the form of an endless belt passing over end rolls, 2, to which power may be applied in any suitable manner (not shown) to drive the screen. As stated, the screen is driven intermittently in the pressing operation. On the upper or operative flight, the screen is supported by a plurality of smaller rolls, 3. A drain box, 4, is placed under the screen to receive the water that drains from the stock and this drain box is provided with an outlet pipe, 5.

The flow box which forms the subject matter of the present invention, consists of a receptacle, 6, which may be of any desired width to place a layer of stock of a desired

size on the screen. The flow box is substantially rectangular in cross section at its upper end and is provided with a rounded bottom, 7, which facilitates the flow of the stock 5 to the outlet, 8, arranged at the bottom of the box. The side walls of the flow box are extended beyond the rounded bottom as indicated at 9 to support a flat bottom plate, 10. This flat bottom plate serves as a support 10 for the motors of the flow box and also serves as a leveling device for the layer of pulp placed on the screen.

A pair of tracks, 11, extend transversely of the screen at a suitable distance from each 15 other. These tracks are supported on transverse beams, 12, mounted on suitable supporting members, 13, arranged at opposite sides of the screen. The tracks are vertically adjustable to permit the flow box to be raised 20 and lowered with respect to the screen and thus vary the thickness of the layer of stock deposited on the screen. At suitable intervals wedge blocks, 14, are mounted on the beams, 12. Similar wedge blocks, 15, are 25 arranged over the blocks, 14, and are laterally adjustable. The rails, 11, are supported on the blocks, 15, so that they will be raised and lowered when these blocks are adjusted on the blocks, 14. The blocks, 15, may be 30 adjusted by means of threaded rods, 16, passing through threaded openings in arms or brackets, 17, carried by the beams, 12. The rails are retained in proper alignment when being adjusted by means of guides, 18, which 35 are arranged at suitable intervals and which may be formed of angle irons secured to the beams, 12.

Suitable means are provided for driving the flow box. As shown, a motor, 19, is 30 mounted on the lower plate, 10, and this motor is adapted to drive a shaft, 20, through suitable reduction gearing, 21. The ends of the shaft extend beyond the flow box (see Fig. 3) and are provided with pinions, 22, 45 adapted to mesh with rack bars, 23, which are coextensive in length with the rails, 11, and are supported in any suitable manner as by the beams, 12. Adjacent the top of the flow box, it is provided with arms, 24, which 50 extend outwardly and form bearings for a pair of shafts, 25, arranged in the front and rear of the flow box. Wheels or rollers, 26, are mounted on these shafts and are adapted to travel on the tracks, 11. As shown in Fig. 55 3 of the drawings the rollers on one side of the flow box and the corresponding track, 11, may be provided with flat faces and the rollers on the other side may be provided with grooves to receive a V shaped rail. It 60 will thus be seen that when the motor, 19, is in operation the flow box will be driven from one side of the screen to the other, the pinions, 22, traveling on the rack bars, 23, to supply the power and the rollers, 26, traveling 65 on the tracks, 11, to guide the flow box.

Stock is delivered to the flow box from a reservoir (not shown) through a feed pipe, 27, which is connected to a transverse feed pipe, 28, by means of a swivel joint, 29, and the transverse feed pipe, 28, is connected to 70 the outlet pipe, 30, by a swivel joint, 31. The swivel joints, 29 and 31 and the pipe, 28, permit the movable outlet pipe, 30, which is mounted on the top of the flow box to travel with the flow box and be connected to the 75 stationary feed pipe, 27. The feed pipe, 30, is connected to a receiving chamber, 32, in the top of the flow box (see Fig. 1) and the bottom of this chamber is provided with a screen, 33, through which stock passes into 80 the flow box. A mixer or beating wheel is mounted in the flow box and is suitably spaced from the rounded bottom wall. The beater wheel is formed of iron spiders, 34, mounted on a suitable shaft, 35, and provided with staves, 36, forming a cylinder. Angle irons, 37, are bolted to the staves and form pockets for agitating the stock and retarding and regulating its passage through the slot, 8, in the bottom of the flow box. 85 The shaft, 35, is carried by bearings, 38, which are slidably mounted in bearing boxes, 39, to permit adjustment of the distance between the beater and the bottom of the flow box. These bearings are carried by rods, 40, 90 which are threaded adjacent their upper ends and pass through threaded openings in clips or brackets, 41, mounted on the flow box (see Fig. 2). Bevelled gears, 42, are arranged on the upper ends of the rods, 40, and mesh with 95 bevelled gears, 43, carried by an adjusting shaft, 44. This shaft projects beyond one side of the flow box and is provided with an operating handle, 45. The two bearings, 38, may thus be simultaneously adjusted by 100 turning the handle, 45, and the shaft, 44. On each side of the outlet opening I provide a flap, 46, which may be made of rubber or other flexible material and when the box is traveling in either direction the front 105 flap is adapted to assume the position shown at the left in Fig. 5 of the drawings to prevent the stock from running ahead of the flow box. The flaps are adapted to swing upwardly and the rear flap is swung to the 110 position shown at the right in Fig. 5 of the drawings by the stock passing through the opening, 8. On one side of the flow box, adjacent the end of the screen or wire farthest from the press the flow of stock is controlled by a deckel, 47, floating on the screen. 115 This deckel may be supported in any suitable manner. On the other side of the flow box the flow is controlled by a deckel, 48, which is carried by the bottom of the flow 120 box and projects downwardly toward the screen. As shown the deckel may be secured to the adjacent side wall of the flow box by bolts, 49, or other suitable fastening elements. Deckels, 50, are arranged at oppo- 125 130

site sides of the screen and when the flow box passes over these deckels which are near the ends of its travel, the pulp flows into the return box, 51, from which it is returned to the reservoir, (not shown) through pipes, 52.

The beater wheel rotates at all times and is driven from a motor, 19, supported on the bottom plate, 10, on the opposite side from the motor, 19. This motor drives a shaft, 54, through suitable reduction gears, 55, which in turn drives a shaft, 56, through gears, 57. The end of the shaft, 56, projects beyond the side of the box and is provided with a sprocket adapted to receive a chain, 58, which passes over a sprocket on one end of the shaft, 35, (see Fig. 2). Stock is delivered to the flow box at all times. When the flow box is in motion the stock delivered is in excess of the amount deposited on the screen. When the flow box is stationary, no stock is deposited on the screen and the excess from the flow box is delivered through a chute, 59, to a box or trough, 60, at one side of the flow box whence it is returned through the pipe, 61, to the reservoir.

The motor, 19, is a reversible motor controlled by suitable means to drive the flow box from one side of the screen to the other and co-ordinate its movements with the movements of the screen so that it will be at rest when the screen is in motion and will travel across the screen when the screen pauses at the end of each operation. Current flows from the line through wires, 79, 81 and 84, to a reversing switch, A, and this switch is provided with a pair of reversing coils, 80 and 89, which control it. A pair of cams, 62, and 63, are mounted on a shaft, 64, which rotates continuously. The shaft 64 may be part of the press or other coordinated apparatus so that the coordinated movement of the screen and flow box will be obtained by closing the switches controlled by cams 62 and 63. These cams are provided with notches, 65, and are adapted to energize the coils, 80 and 89, respectively. The shaft travels 180° for each movement of the flow box. The starting switches are each provided with a movable dog, 66, adapted to enter the notch, 65, and when one of these dogs enters the notch as indicated to the right of Fig. 8 of the drawings, the arm 66 contacts with a stationary contact, 67. The contacts, 66 and 67, are connected to lead wires, 68 and 69, respectively. These lead wires pass through contacts, 70 and 71, on a manually controlled switch controlled by a handle, 72, and the lead wire, 68, is then connected to a connection, 73, extending to a contact element, 74, of a limit switch and adapted to be engaged by a movable contact element, 74'. The limit switch is arranged adjacent the end of the path of travel of the flow box. The limit switch is provided with a second contact ele-

ment, 75, and is also provided with an arm, 76, adapted to be engaged by an arm, 77, carried on the end of the flow box. From the contact element, 74', a lead wire, 78, is connected to one of the line wires, 79.

The other lead wire, 69, from the cam shaft after passing through the hand switch passes through the reversing coil, 80, and thence to line wire, 81, so that the coil is energized from the line side when the cam switch 75 and the limit switch are closed. When the coil, 80, is energized the switch elements, 82 and 83, in the line wires are closed and current from the line flows through these wires and a common wire, 84, to the motor, 19, to 80 revolve it in one direction. The reversing coil, 80, is only momentarily energized from the line side of the switch as the revolution of shaft, 64, opens the cam switch, but as soon as the switch is closed the coil is energized 85 from the load side. As shown switch element, 82, is connected to a movable switch element, 106, by a wire, 82', and when coil, 80, is energized, it engages a stationary contact, 105. From the contact, 105, current flows through 90 wire, 150, to the other element, 75, of the limit switch. From the limit switch current flows through wire, 151, to contact, 152, of a hand switch, 110, which is normally closed, and from contact, 153, of the hand switch 95 through a wire, 154, to the coil, 80. Coil, 80, is thus in series with the limit switch and hand switch, 110.

The cam, 63, and its cam shaft are likewise adapted to momentarily energize reversing 100 coil, 89, through lead wires, 85 and 86. These wires also pass through switch elements of the manually operated switch 72. The wire, 85, being connected to a switch element, 87, and the wire, 86, being connected to a switch element, 88. From the switch element, 87, the wire, 85, is connected to coil, 89, thence to the line wire, 81. The coil, 89, is arranged opposite the coil, 80, and is adapted to control the connections to the reversing switch, A, of 110 the motor to revolve the motor in the opposite direction. The switch element, 88, is connected to a lead wire, 90, extending to a limit switch, 91, arranged at the opposite end of the path of travel of the flow box and connected 115 to an arm, 92, which will be engaged by the arm, 77, on the opposite end of the flow box. The opposite side of the limit switch is provided with a connection, 93, connected to the wire, 78, and thence to line wire, 79. Line 120 wire, 79, is provided with a branch, 94, and line wire, 81, is similarly provided with a branch, 95, connected to stationary contacts, 96 and 97, and the coil, 89, is adapted to control a pair of switch elements, 98 and 99, 125 through which the circuit may be completed to the lead wires connected to the motor, 19, to revolve it in the opposite direction. Switch element, 98, is connected to a switch, 107—108, similar to the switch, 105—106, by 130

means of which the coil, 89, is energized from the load side of the reversing switch after the switch has been closed, and the cam switch opened by movement of cam, 63. Switch, 5 107—108, is connected to the second element of limit switch, 91, by a wire, 155, and from the limit switch current flows through wire, 100, to hand switch, 101, thence through wire, 102, to the coil, 89.

10 When washing the flow box, or when it is
to be disconnected from the screen for any
other purpose, the cam switches, 66—67, are
opened and the motor is controlled by the
hand switches, 101 and 110. The hand
15 switches are provided with means for ener-
gizing the coils from the line side of the re-
versing switch in place of the cam switches,
62 and 63. As shown switch, 110, is provided
with a second movable contact above the sta-
20 tionary contact, 153, adapted to connect it to
a stationary contact, 156. Current then flows
from line wire, 81, through coil, 80, wire, 154,
contact, 153, contact, 156, wire, 157, to wire,
73, thence through the limit switch element
25 74', in the manner heretofore described and
back to the line wire, 79. Switch, 101, may
likewise be used to initially energize coil, 89,
if the limit switch, 91, is closed.

As the shaft, 64, revolves, the switches, 30 66—67, are alternately closed. When the switch to the right is closed the coil, 80, is energized moving the contacts, 82 and 83, into operative position and connecting the circuit through line wire, 79, 81 and 84, to 35 the flow box motor, 19, to revolve it in one direction. The circuit is opened by the limit switch, 74—75, when the flow box reaches the end of its path of travel. The other dog, 66, then drops into the notch, 65, of the cam, 63. 40 The coil, 89, is then energized, reversing the main switch and the two phase current then flows through the switch elements, 98 and 99, from the wires, 79 and 81, and through the common wire, 84, which is closed at all times 45 to the motor, 19, reversing the direction of the motor whence it travels in the opposite direction until stopped by the limit switch, 91. When the flow box is operated by hand the cam switches 66—67, are cut out and the coils, 50 80 and 89, energized by the hand switches, 101 and 110.

As the flow box travels across the screen, a layer of stock is deposited on the screen as indicated in Fig. 1 of the drawings. As the flow box travels in either direction the flap, 46, in front assumes the operative position shown in Fig. 5 of the drawings to prevent the stock from flowing in front of the box. The flat bottom plate, 10, of the flow box smoothes the upper surface of the layer of stock. The thickness of this layer may be adjusted by vertically adjusting the tracks, 11, by means of the wedges, 14 and 15, which raise or lower the entire flow box. The beater wheel in the flow box may likewise be ad-

justed through the shaft, 44, which is operated by the handle, 45. Excess stock is returned to the reservoir from the flow box through the chute, 59, and the stock which flows over the edges of the screen is caught in the return boxes, 51. The deckels, 47, and 48, at each side of the flow box control the flow of stock longitudinally of the machine and the edge of the board on the screen ahead of the one being formed also aids in confining the stock. 75

When the flow box is at rest, one limit switch is open, and as current from phase wire, 79, must pass through one of the limit switches before the corresponding reversing coil can be energized, only one movement of the flow box is possible, namely, in the direction controlled by the closed limit switch, which rotates the motor in the right direction. One element of each of the hand switches, 101 and 110, is also in series with one element of each corresponding limit switch. This safeguards the flow box for over travel, as it is impossible to move it beyond the limits of its normal travel, or in the wrong direction by either the cam switch or hand switch.

Various fibrous products may be made by means of this apparatus. In addition to wall board, composition building boards, insulating boards and other composition materials may be made. At the present time these products are made on a continuously moving screen on which the pulp is deposited, then passed through squeeze or suction rollers to eliminate some of the water, and then through a dryer without severing the pulp until it emerges from the dryer in the form of a finished product, when it is cut into sheets of desired sizes. So far as I am aware, my process of forming a fiber mat on a screen without the use of a mould, and then moving the screen intermittently between the platens of a press to remove a large portion of the water, is novel.

I claim:

1. In combination with an intermittently moving screen, a flow box adapted to travel transversely of the screen, a rotating shaft, and switches controlled by the shaft to actuate the flow box when the screen is at rest. 110
  2. In combination with an intermittently moving screen, a flow box adapted to travel transversely of the screen, a rotating shaft, cams mounted on said shaft, and switches controlled by said cams and adapted to actuate the flow box. 115
  3. In combination with an intermittently moving screen, a flow box adapted to travel transversely of the screen, a rotating shaft, switches controlled by the shaft to actuate the flow box when the shaft is at rest, and limit switches arranged at the ends of the path of travel of the flow box. 120
  4. In combination with an intermittently moving screen, a pair of tracks extending transversely thereof, a flow box adapted to 130

travel on said tracks, and means for controlling the movement of the flow box.

5. In combination with an intermittently moving screen, a pair of tracks extending transversely thereof, a flow box adapted to travel on said tracks, and a motor carried by the flow box to cause said flow box to travel on said tracks.

10. In combination with an intermittently moving screen, a pair of tracks extending transversely thereof, a flow box adapted to travel on said tracks, a motor carried by the flow box to cause said flow box to travel on said tracks, a rotating shaft and switches actuated by said shaft to control the movement of the flow box.

15. In combination with an intermittently moving screen, a pair of tracks extending transversely of the screen, a flow box, rollers mounted on the flow box and adapted to travel on said tracks, rack bars arranged parallel to said tracks, a drive shaft carried by the flow box, and pinions mounted on said shaft and meshing with said rack bars.

20. In combination with a movable screen, a movable flow box mounted over the screen, said flow box being provided with a flat bottom plate to form a level surface on a layer of stock deposited on said screen by said flow box.

25. In combination with a movable screen, a movable flow box mounted over the screen, said flow box being provided with a flat bottom plate to form a level surface on a layer of stock deposited on said screen by said flow box and means for adjusting said flow box with respect to said screen to regulate the thickness of the layer of deposited stock.

30. In combination with a movable screen, a movable flow box adapted to deliver stock to said screen, said flow box being provided with an outlet slot in the bottom thereof, and flaps arranged adjacent said slot, one of which is adapted to bridge the space between the flow box and the screen as the flow box travels in either direction to prevent the stock from the flow box from flowing in front of it as it travels over said screen.

35. In combination with an intermittently moving screen, an intermittently moving flow box, means for continuously delivering stock to the flow box and means for returning excess stock to the reservoir.

40. In combination with a movable flow box, a stationary feed pipe, a connecting pipe, and swivel joints arranged at each end of said connecting pipe.

45. In combination with an intermittently moving screen and an intermittently moving flow box, means for continuously delivering

stock to said flow box, a return box arranged on the side of the flow box and a chute connecting the flow box to the return box.

50. In combination with a movable screen, a movable flow box adapted to travel over said screen, and means for adjusting said flow box with respect to said screen to regulate the thickness of the layer of stock deposited.

55. In combination with a movable screen, a pair of tracks arranged over said screen, a flow box adapted to travel on said tracks to deposit a layer of stock on the screen, and means for adjusting the height of said tracks to regulate the thickness of said layer of stock.

60. In a device of the character described, a screen, a flow box arranged over said screen and having an outlet slot in the bottom of the flow box, and a pair of hinged flaps mounted on opposite sides of said slot, one of which is adapted to be moved into operative position as the flow box travels in either direction.

65. In a device of the character described, a screen, a flow box having a flat bottom plate to form a level layer of stock on the screen, and a drive motor supported on said plate.

70. In combination with a screen, a flow box adapted to travel over said screen, means for reversing the direction of travel of said flow box, and means for stopping said flow box at the end of each movement.

75. In combination with a screen, a flow box adapted to travel over said screen, switches for controlling the movement of said flow box, and means for automatically actuating said switches.

80. In combination with a screen, a flow box adapted to travel over said screen, switches for controlling the movement of said flow box and cams for actuating said switches.

85. In combination with a screen, a flow box adapted to travel over said screen, automatically operated switches to control the movement of said flow box in either direction, and limit switches to stop said flow box at the end of each movement.

90. In combination with an intermittently moving screen, a flow box adapted to travel transversely of said screen, means for reversing the direction of travel of said flow box, and means for stopping said flow box at the end of each movement.

95. In combination with an intermittently moving screen, a flow box adapted to travel transversely of the screen, means for driving said flow box in either direction, automatic means for controlling the actuation of said flow box, and means for limiting the movement of said flow box in either direction.

In testimony whereof I affix my signature.
EDWIN H. STREETER.
